US00D716368S

(12) **United States Design Patent**
Uesugi et al.

(10) **Patent No.:** US D716,368 S
(45) **Date of Patent:** ** Oct. 28, 2014

(54) **BENDER LEVER FOR AN ELECTRONIC MUSICAL INSTRUMENT**

D668,710 S * 10/2012 Okamura et al. D17/1

* cited by examiner

(71) Applicant: **Roland Corporation**, Shizuoka (JP)

Primary Examiner — Rashida Johnson

(74) Attorney, Agent, or Firm — Jianq Chyun IP Office

(72) Inventors: **Tetsuya Uesugi**, Shizuoka (JP); **Hitoshi Sato**, Shizuoka (JP)

(57) **CLAIM**
The ornamental design for a bender lever for an electronic musical instrument, as shown and described.

(73) Assignee: **Roland Corporation**, Shizuoka (JP)

DESCRIPTION

(**) Term: **14 Years**

(21) Appl. No.: **29/465,526**

(22) Filed: **Aug. 29, 2013**

FIG. 1 is a perspective view of a bender lever for an electronic musical instrument showing a first embodiment of our new design;

(51) **LOC (10) Cl.** 17-01

FIG. 2 is a front view of the first embodiment;

(52) **U.S. Cl.**

FIG. 3 is a rear view of the first embodiment;

USPC **D17/9**

FIG. 4 is a left side view of the first embodiment;

(58) **Field of Classification Search**

FIG. 5 is a right side view of the first embodiment;

USPC ..... D17/1, 2, 7-9; 84/13, 19, 423 R, 424,

FIG. 6 is a top view of the first embodiment;

84/426, 427, 443, 719, 720, 744, 745;

FIG. 7 is a bottom view of the first embodiment;

D21/409

FIG. 8 is a reduced perspective view of the first embodiment, in a state of use;

See application file for complete search history.

FIG. 9 is a perspective view of a bender lever for an electronic musical instrument showing a second embodiment of our new design;

(56)
